UNITED STATES PATENT OFFICE.

HORATIO R. SWARTWOOD, OF KANSAS CITY, MISSOURI, ASSIGNOR OF ONE-THIRD TO HAZEL VICK, OF ATCHISON, KANSAS, AND ONE-THIRD TO MILDRED M. O'CONNOR, OF KANSAS CITY, MISSOURI.

SASH BALANCE AND FASTENER.

Application filed August 18, 1921. Serial No. 493,380.

To all whom it may concern:

Be it known that I, HORATIO R. SWARTWOOD, a citizen of the United States, residing at Kansas City, in the county of Jackson and State of Missouri, have invented a certain new and useful Improvement in Sash Balances and Fasteners, of which the following is a specification.

My invention relates to improvements in sash balances and fasteners.

The object of my invention is to provide a simple, cheap and effective sash balance combined with means for locking the sash in the position to which it may be adjusted.

A further object of my invention is to provide a device of the kind described, which may be readily applied to windows already installed, which is durable and not liable to get out of order and which is efficient in operation.

The novel features of my invention are hereinafter fully described and claimed.

In the accompanying drawing, which illustrates the preferred embodiment of my invention,

Fig. 1 is a front view, partly in elevation and partly broken away, of a window provided with my improvement.

Fig. 2 is a vertical sectional view of the same.

Fig. 3 is an enlarged horizontal section on the line 3—3 of Fig. 1.

Fig. 4 is a vertical sectional view on the line 4—4 of Fig. 3.

Fig. 5 is a vertical sectional view on the line 5—5 of Fig. 4.

Similar reference characters designate similar parts in the different views.

1 designates an ordinary window frame having a jamb 2. 3 and 4 designate the upper and lower sashes respectively, each of which is provided in one side edge with a vertical groove 5, in which is mounted a vertical coil spring 6.

The coil spring 6 which is mounted in the lower sash 4, has its lower end secured in the groove 5 to the sash 4, its upper end being extended through a hole 7 in the frame 1 and

attached to a pin 8 mounted on the frame, the coil spring which supports the upper sash has its lower end attached thereto and at its upper end it extends through the frame 1 and into a vertical tube 9 which is mounted on the frame 1 and which has a closed upper end to which the spring is attached. If desired, each of the sashes may be provided, as shown in the drawing, in opposite side edges with two grooves in which are respectively mounted and secured, in the manner described, two coil supporting springs.

Each sash has secured to one of its side edges, a vertical plate 10 which covers the adjacent groove 5, and which is provided with a longitudinal row of holes 11, see Fig. 2.

For releasably locking each sash in the position to which it may be adjusted, there are provided suitable means which may comprise two locks, each of which is mounted in the frame 1 at one side and near its middle, and each of which is provided with means for being manually unlocked.

As the two locks are similar in construction, a description of the one which operates in connection with the lower sash is sufficient for both.

Referring to Figs. 3, 4 and 5, the lock comprises a rectangular casing 12, having a removable side 13 and a vertical plate 14 which is fastened to the jamb 2 by screws 15.

Horizontally slidably mounted in the casing 12 is a bolt 16, which at its outer end is adapted to enter any one of the holes 11 in the lower sash. For normally forcing the bolt to the locking position, it is provided with a longitudinal slot 17, in which is mounted a horizontal coil spring 18, one end of which bears against the bolt 16 and the other end of which bears against a projection 19, which extends inwardly into the slot 17, from the casing 12.

For manually retracting the bolt 16 from the locking position, there is provided in the casing 12 an oscillatable member 20 having cylindrical shouldered ends respectively

mounted in holes in the front and rear of the casing 12, and which is mounted between the two arms of the bifurcated adjacent inner end of the bolt 16, and which is provided with two oppositely extending arms 21 which respectively engage on the same side two projections 22 on the bolt 16. The member 20 is provided with a hole which extends longitudinally therethrough, and which is other than round in cross section. Through this hole extends a horizontal forwardly and rearwardly extending shank member 23 which fits the hole and which extends through a hole 24 in the frame 1. The member 23 is shouldered at its forward end, and is rotatably fitted in a hole in a plate 25 which is fastened to the inner side of the frame 1. A knob 26 is secured to the front end of the shank member 23.

20 By turning the knob 26 in either direction, the shank member 23 operates to turn the member 20 so that the latter withdraws the bolt 16 from the locking position, and out of the adjacent hole 11 in the adjacent plate 10.

25 The sash 4 may then be vertically adjusted to the desired position, after which the knob 26 is released, upon which the spring 18 will force the bolt 16 to the locking position, in which the bolt will enter the hole 11 which is then in register therewith.

The lock for the upper sash is constructed and operated in the same manner, as above described, the shank 23 of the upper lock being longer to correspond with the greater distance of the casing of the upper lock from the inner side of the window frame.

The springs 6 are preferably of sufficient strength to lift the sashes to their uppermost positions.

40 To raise the lower sash, it is but necessary to operate the knob 26 of the lower lock so as to withdraw the adjacent bolt 16 from the locking position, upon which the adjacent springs 6 will lift the sash 4. The latter may be stopped at the desired elevation and the knob 26 released, upon which the bolt will re-engage the sash and lock it in the adjusted position.

When it is desired to lower the upper sash, the upper knob 26 is turned to unlock the adjacent bolt, after which the upper sash is pulled downwardly to the position desired and the knob then released, thereby permitting the adjacent bolt to re-engage the upper sash and lock it in its adjusted position.

The holes 11 may be so arranged as to permit both sashes to be locked in the closed position.

By having the coil springs 6 located in longitudinal grooves in the edges of the sashes, longitudinal slotting of the jambs is avoided, and the invention is applicable to window frames having single jambs fitted against brick or stone, or against studding,

as well as to box window frames. With 65 this construction the plates 10 serve the double function of locking plates, and co-operate with the sashes to form housings for the coil supporting springs.

By having the locks located in the window frame, the knobs 26 are each located permanently at one place, so that a person can readily locate them in the dark.

I do not limit my invention to the structure shown and described, as modifications 75 within the scope of the appended claims may be made without departing from the spirit of my invention.

What I claim is:—

1. In a sash balance and fastener, the combination with a window frame and a sash 80 slideable therein, of a plate secured to the sash and having a vertical row of holes, a bolt adapted to be moved on said frame into and out of any one of said holes, and a vertical coil spring supported by the frame and supporting the sash, substantially as set forth.

2. In a sash balance and fastener, the combination with a window frame and a sash 90 slideable therein, of a vertical coil spring supported by the frame and supporting the sash, bolt engaging means on said sash, and a lock mounted on the frame and comprising a casing, a bolt slideable in the casing, a spring normally forcing the bolt into engagement with said bolt engaging means, and manually operated means for retracting the bolt from said position, substantially as set forth.

3. In a sash balance and fastener, the combination with a window frame, of a sash 95 slideable therein having in one side edge a vertical groove, a vertical coil spring supported by the frame and mounted in said groove and attached to and supporting said sash, a vertical plate fastened to said sash and covering said groove and having a vertical row of holes, a lock casing mounted in said frame, and a bolt mounted in said casing and movable to and from a position in which it is adapted to enter any one of said holes, substantially as set forth.

4. In a sash balance and fastener, the combination with a window frame, of a sash slideable therein having in one side edge a vertical groove, a vertical coil spring mounted in said groove and having its upper end attached to the frame and its lower end attached to the sash, a vertical plate attached to said edge and having a vertical row of holes, a lock casing mounted in the frame, a bolt slideable in said casing to and from a position in which it is adapted to enter any one of said holes, a spring for forcing the bolt to a locking position, and manually operated for retracting the bolt from the locking position, substantially as set forth.

5. In a sash balance and fastener, the combination with a window frame, of a sash slidable therein having in each longitudinal edge a vertical groove, two coil springs having their upper ends supported by the frame and respectively mounted in said grooves and attached at their lower ends to and supporting the sash, and releasable means for locking the sash to the frame, substantially as set forth. 10

In testimony whereof I have signed my name to this specification.

HORATIO R. SWARTWOOD.
